US00D918187S

(12) **United States Design Patent** (10) **Patent No.:** **US D918,187 S**
Feit et al. (45) **Date of Patent:** **** May 4, 2021**

(54) **ANTENNA**

(71) Applicant: **Antennas Direct, Inc.**, Ellisville, MO (US)

(72) Inventors: **Corey Feit**, St. Louis, MO (US); **John Edwin Ross, III**, Moab, UT (US); **Richard E. Schneider**, Wildwood, MO (US)

(73) Assignee: **Antennas Direct, Inc.**, Ellisville, MO (US)

(**) Term: **15 Years**

(21) Appl. No.: **29/754,912**

(22) Filed: **Oct. 15, 2020**

CLAIM

The ornamental design for an antenna, as shown and described.

DESCRIPTION

FIG. 1 is a perspective view of an antenna showing our new design;

FIG. 2 is a front view thereof;

FIG. 3 is a right side view thereof;

FIG. 4 is a left side view thereof;

FIG. 5 is a top view thereof; and,

FIG. 6 is a front view thereof.
